UNITED STATES PATENT OFFICE

PIETER MIJER, OF NEW YORK, AND LESTER C. SCOTT, OF BROOKLYN, NEW YORK, AND
GEORGE S. RADFORD, OF NEW CANAAN, CONNECTICUT, ASSIGNORS, BY MESNE
ASSIGNMENTS, TO TWO-TONE CORPORATION, OF NEW YORK, N. Y., A CORPORATION
OF NEW YORK

APPARATUS FOR DYEING, COLORING, AND COATING

Application filed February 23, 1928, Serial No. 89,830, and in Hungary March 7, 1925.

This invention relates to an improved apparatus for dyeing or coloring fabrics such as textile fabrics, or for dyeing or coloring any other articles, and relates more particularly to an improved apparatus of dyeing materials or articles preferably in the form of a continuous web, such as continuous pieces of ribbon, silk, cotton, linen and the like; the apparatus is also applicable to the uniform coating of continuous webs of fabric and other articles or materials with liquids of all classes and descriptions. Our improved apparatus is particularly applicable for the dyeing of textile fabrics either on one or both sides thereof, either with the same color or with different tones of the same color, or with different colors.

Among the objects of our invention is to provide an improved apparatus for uniformly dyeing a textile fabric either on one or both sides thereof, while positively controlling the amount of color applied to the web of textile fabric or other article being treated. A further object of the invention is to provide an improved apparatus adapted for continuous operation utilizing a so-called color cloud composed of minute particles of atomized dye liquor, coloring matter or other liquid, without the formation of drops or objectionable spots upon the fabric. A further object of the invention is to provide a color cloud made up of extremely fine particles of color or dye stuff. A further object of the invention is to feed the material to be treated relative to the color cloud or in such manner that said material presents a flat surface to said color mass while exposed thereto. A further object of the invention is to provide an improved textile fabric coated or dyed on one or both sides thereof with minute particles of coloring matter deposited thereon by means of the process herein described.

The present invention is an improvement on the inventions described in the prior patent applications of Pieter Mijer, Serial No. 692,762, filed February 14, 1924; Serial No. 723,166, filed June 30, 1924; Serial No. 723,167, filed June 30, 1924; Serial No. 724,262, filed July 5, 1924; Serial No. 725,100, filed July 10, 1924, and Serial No. 726,249, filed

July 16, 1924. A preferred embodiment of the invention will now be described with reference to the accompanying drawings, in which:

- Fig. 1 is a side elevation of the apparatus; 55
Fig. 2 is a vertical longitudinal section; 60
Fig. 3 is an elevation of the entering end of the machine; 65
Fig. 4 is an end view of the exit end of the machine; 70
Fig. 5 is a horizontal section on the line 5—5 of Figure 2; 75
Fig. 6 is a cross-section on the line 6—6 of Figure 2; 80
Fig. 7 is a plan; 85
Fig. 8 illustrates the driving mechanism more or less diagrammatically on line 8—8 of Figure 2, and 90
Fig. 9 shows the atomizer in enlarged section elevation. 95

Referring to the drawings, the mechanism comprises broadly the cloud generating means A, the dye application chamber B, and the drying means C. A cloud of minute particles of atomized dye liquor or coloring matter is generated in chamber A, passes to dye chamber B, where it is applied to the fabric, and the fabric is thereafter dried in the chamber C. The generating chamber A is provided with a roof 10 to which is hinged a door 11 with sight window 12 (Fig. 2). Adjacent said window 12 (Fig. 2) is a bank of atomizing nozzles 13, which nozzles serve to atomize the dye liquor, coloring matter or coating liquid, and break it up into extremely minute particles which pass in the form of a cloud from the chamber A to the chamber B. Said chamber A furthermore serves as a separating chamber; that is to say, heavy particles of dye liquor which may pass out of the nozzles, or may be formed in the operation of the nozzles, drop on the floor of the chamber A, while the lighter particles pass into the chamber B. Each of the nozzles 13 are connected by pipes 13' (see Fig. 3) with a header 14 (Fig. 1) and the passage of liquid into each of said pipes 13' from the header 14 is controlled by cocks 15. A needle valve 16 controls the connection between pipe 17 connected to dye tank 18 and header 14, 100

whereby fine adjustments of the total quantity of liquid passing to the atomizers can be effected. Pipe 19 controlled by cock 20 admits air under pressure to tank 18 (Fig. 4) whereby to positively force dye liquor or other liquid in tank 18 into the bank of atomizer nozzles 13. Pipe 21 leads compressed air or other suitable atomizing medium to the atomizer nozzles, and is controlled by cock 22 (Fig. 3). It will be noted that the roof 23 of the cloud generating chamber A is curved as shown (see Fig. 3) and inclines to the end wall 24 (Fig. 2) of chamber B. Referring to Fig. 2, chamber B has its front end wall 24 formed with an opening 25 constituting a passage between chamber A and chamber B, through which the cloud of atomized dye can pass from the generating chamber to the dye chamber. That portion 26 of wall 24 forms a baffle to prevent large drops passing from chamber A to chamber B. A shield 27 projects into dye chamber B and serves to obstruct large drops or large particles which may pass from chamber A to chamber B, from dropping on to the textile fabric or the like at the bottom of said chamber. Referring to Fig. 5, it will be seen that spaces 28, 29 between the longitudinal walls of the dye chamber, and space 30 between the end of the shield and the end wall 31 (Fig. 2) of the dye chamber, permit the cloud of dye particles to pass from the upper part 32 of chamber B to the lower part 33 (Fig. 2) of the said chamber. To prevent drops forming on any of the edges of said shield 27, the edges of this shield are formed by steam pipes 34 receiving steam from pipe 35 controlled by cock 36 (Fig. 5) and connected to a source of steam supply. The pipe 34 at the outermost edge of apron 27 is connected by pipes 37 and 38 with steam cock 39 (Fig. 5). A heavy endless belt 40 (Fig. 2) of canvas or the like, which will lie flat in operation, passes over a curved bed 41 at the bottom of chamber B; it passes over rollers 42, 43 mounted on shafts 44, 45, and suitably driven as more particularly described with reference to Fig. 8. Said belt passes through slots 46, 47, in the end walls 24, 31, and the edge of each of said slots is formed by steam headers 48, 49 connected together by longitudinal steam pipes 50, header 49 being connected to exhaust by pipe 51 controlled by cock 52 (Fig. 5) and header 48 being connected to cock 39 by pipe 53. The drying chamber C comprises a steam coil 54 connected at one end with cock 39 and at the other end with cock 55 leading to exhaust 56. Said steam coil is arranged beneath the belt 40 and serves to dry the belt and the fabric thereon, as it passes through the slots 57 and 58 (Fig. 2) in the casing 59 of the drying chamber. A glass door 60 in casing 59 permits of observation and entry to chamber C, and glass door 61 (Fig. 1) on each side of

chamber B permits of observation and entry to chamber B. The conveyor belt driving mechanism is illustrated more particularly in Figs. 7 and 8, and comprises a motor 62 and driving belt 63 connected to a Reeves change speed gear 64, or other suitable change speed gearing (illustrated diagrammatically) and connected by belt 65 with speed-reducing mechanism 66 connected by chain 67 with sprocket 68 on shaft 44 of belt-driving pulley 42. Chain 69 connects sprocket 70 on shaft 44 with sprocket 71 on shaft 72 journaled in bearings 73 which shaft 72 supports a take-up roller 74 which receives the fabric. It will be understood that on operation of the motor switch, said motor drives through the aforesaid mechanisms, the belt pulley 42 and the take-up roller 74.

Where the machine is employed for dyeing ribbons or other materials which lie flat on the belt with or without tension, the above belt feeding mechanism operates satisfactorily, but where certain kinds of broad cloth, broad silk, etc., are treated, we prefer to provide means for laying the material flat upon the belt. To this end, we may if desired provide a spreader roller 75 at the incoming end of the machine, said spreader roller being journaled in bearings 76 and suitably driven. Idler roller 80 is journaled in bearing 76. The broad silk being fed into the machine passes over idler roller around spreader roller 75 which lays the material flat on belt 41. The spreader roller may be of any well known type having sufficient grip on the fabric or material to stretch the same transversely and prevent the formation of longitudinal wrinkles, as for example, the Van Vlaaderen spreader roll made at Paterson, N. J., U. S. A.

Inasmuch as the operation of such spreader rollers is well known in the textile art, the same will not be described further herein.

It will be noted that the cloud chamber A and the upper portion of dye chamber B provide a long path for the particles coming from the bank of atomizing nozzles 13. Obviously, when these particles leave the atomizers, they have a certain velocity. It has been noted that when these particles are under a substantial velocity and meet obstructions, they tend to coalesce on the obstruction, forming drops which are carried by the pressure obtained in chamber A into chamber B. Moreover, where the particles are under considerable velocity, if they should strike an obstruction, they would tend to form drops on this obstruction. It is, therefore, an important feature of the invention that particles traveling under substantial velocity do not come into contact with any obstructions. By the time the particles are within the chamber B, they have substantially lost their velocity and pass down under gravity. Coalescing or drop formation

on the wall 31 is thus avoided, although if any drops should form, they do not fall upon the fabric because they are evaporated by the steam header 47.

While any suitable atomizing devices may be employed which will produce a finely divided spray, we prefer to employ atomizing nozzles having permanently set nozzles such as those made by the Parks Cramer Company, of Fitchburg, Mass., of U. S. A. These atomizing nozzles present the important advantage that they do not require setting, as is the case with the air brushes of the type employed in the earlier co-pending applications hereinbefore referred to. Where any clogging up of the brushes takes place, they can readily be cleaned by the application of a brush through the door (12). These atomizing means are illustrated in section in Fig. 9, from which it will be seen that each atomizer is composed of two parts, 80, 81, part 80 enclosing a chamber 82 into which is suitably screwed the nozzle 81. Air is admitted into chamber 82 through connection 83, while the dye liquid is introduced into nozzle 81 through connection 84. Said nozzle 81 is formed with a fine median passage 85, through which the liquid passes to the needle end 86. This needle end is adjusted with reference to an aperture 87 leading into chamber 82, and the curved walls 88 of said chamber 82 direct the compressed air in said chamber into the desired atomizing relation with the liquid issuing from nozzle 87. In the preferred form of the invention, the atomizing medium, such as compressed air, is supplied at high pressure, whereby the liquid issuing from the atomizing nozzle is immediately broken up into extremely minute particles. Preferably the compressed air is supplied by pressures from 115 to 120 lbs. per square inch or higher. We may also feed the liquid under pressure by means of the pressure feed on the liquid tank heretofore described, and it is preferred to feed said liquid at a pressure of around 40 lbs. per square inch. It is to be noted that owing to the fact that both the air and the liquid are under positive control, while the amount of liquid supplied does not depend upon the amount of compressed air supplied, nor does it depend upon the pressure of said compressed air, the quantity of dye liquor in chamber B is at all times under the positive control of the operator, so that he can determine with substantial exactitude the amount of dye atomized per minute.

We will now proceed to describe the operation of our improved process, employing the apparatus hereinbefore referred to. We prefer to carry out the process with raw or virgin silk which has been boiled off according to usual practice before it has been sized or finished. The silk is ironed or smoothed to remove any wrinkles therefrom. The desired

amount of color to be used having been determined, the atomizing nozzles are set in operation by turning on the compressed air and liquid dye, the air pressures being suitably regulated, and the quantity of liquid fed into the bank of nozzles being regulated by needle valve 16. A leader cloth or web is fed into the dye chamber to cover the belt 40 on the bottom thereof, and the free end thereof is attached to winding-up roller 74. The silk is not fed into the machine until a balanced cloud is built up within the dye chamber, and by a balanced cloud we mean a cloud in which the amount of atomized particles which are being fed into the cloud is about the same as the amount of particles which are deposited on the bottom of the dye chamber B and on the fabric. Such a stable or balanced cloud takes a considerable time to build up, but experience soon enables the operator to determine the time element. Where the cloud is too small in chamber B at the beginning of the dye operation, that portion of the fabric which is first dyed will be lighter in color than the portions which are dyed ten or fifteen minutes later. After having established stable conditions in respect of said cloud, the fabric to be colored is fed into the machine and can be dyed either on one side or throughout its thickness. We shall first describe the operation with reference to dyeing one color on one side and another color on another side. The material passes along the bottom of the dye chamber along with the leader cloth, and is exposed to the cloud of atomized coloring matter, the minute particles of which are deposited thereon and produce a color surface thereon, without, however, passing through to the other side of the material. After passing through dye chamber B, the material passes into drying chamber C where it is dried by the action of the steam coil 54 therein; it then passes to winding roller 74. After the material has been dyed on one side thereof, it can be dyed in a similar apparatus with a different color or different shade of the same color on the other side thereof. We may provide an intermediate steaming of the material after it has been dyed on one side, before it has been dyed on the other, or we may steam the material after it has been dyed on both sides. It is important that the material should be kept flat during the steaming operation, and it is preferred that the steam shall be "wet", as is common in steamers used in the printing art. In the preferred operation of the process, good results have been obtained with the humidity indicated by a difference of four degrees between the wet and dry bulb readings in a steaming and ageing machine. The effect of the steaming operation appears to be to spread the minute microscopic particles of color on the fabric, so as to tend to make them merge into one another, and also to set these color particles in the fibres.

By the employment of the spreader roll 75, the material such as silk or the like is laid flat upon the conveyor belt before it passes into the dye chamber. The high pressure atomization which takes place in the present apparatus creates a cloud having extremely fine particles, which particles appear to be uniform in character and do not tend to coalesce. That zone where coalescence is likely to take place is contained within the chamber A and above the apron 27 of chamber B, so that larger particles, no matter whether they are created by condensation, coalescing or spitting of the atomizers, do not fall upon the fabric and cause spots. Any particles or drops forming on the edges of apron 27 or slots 46, 47, are immediately evaporated by the aforesaid steam pipes. We prefer to filter the color prior to leading it to the atomizer in any suitable manner, and to employ the dye in concentrated solution. It will be appreciated that an apparatus in accordance with the present invention provides a color cloud capable of dyeing without the formation of drops; that is, the concentration of sufficient dye liquor to pass entirely through the fabric and to form a spot in the fabric at this point which is differentiated in color from the color field or color ground around it. We differentiate between "drop" and the minute particles which make up the cloud, and we differentiate between "spots" on the textile fabric and the minute specks of color produced by the minute particles of the cloud.

While the improved process and apparatus have been described with reference to a preferred embodiment thereto, it will be obvious to those skilled in the art that modifications or variations can be imported into the said process and apparatus without departing from the scope of the invention.

What we claim is:

1. An apparatus for cloud dyeing textile fabrics comprising a dye application chamber, and a cloud generating chamber external thereto and communicating therewith, and of sufficient extent to permit separation of dye drops before the cloud enters the dye application chamber.

2. An apparatus for dyeing textile fabrics, comprising a dye application chamber, an atomizing chamber external thereto, of sufficient extent to permit separation of drops from the atomized liquid, and atomizing means in said atomizing chamber.

3. An apparatus for dyeing textile fabrics, comprising a dye application chamber, an apron extending substantially across said dye chamber to support the fabric to be dyed, and means for providing a dye cloud in said chamber.

4. An apparatus for dyeing textile fabrics, comprising spray means for atomizing a liquid at high pressure to form a cloud, means for providing a long path for the high pres-

sure atomized spray from which the cloud is formed to permit separation of large drops from the spray, and means for feeding material to be treated relative to said cloud.

5. An apparatus for dyeing textile fabrics, comprising an atomizing chamber, a dye application chamber communicating therewith, and shielding means extending across the dye application chamber between the top and bottom thereof but permitting substantial communication between the upper and lower portion of the dye application chamber.

6. In an apparatus for dyeing textile fabrics, an atomizing chamber, a dye chamber communicating therewith, and a shield extending into the dye chamber and means for preventing the formation of drops on the edge of said shield.

7. In an apparatus for dyeing textile fabrics, a shield extending across the dye chamber and a steam pipe forming the edge of said shield.

8. An apparatus for dyeing textile fabrics, comprising a closed dye-applying chamber, a closed atomizing chamber external thereto but communicating therewith, and a travelling apron passing through the dye-applying chamber to support a fabric travelling therethrough.

In testimony whereof, we hereto affix our signatures.

PIETER MIJER.
LESTER C. SCOTT.
